US00D999346S

(12) **United States Design Patent** (10) **Patent No.:** **US D999,346 S**
(45) **Date of Patent:** **** Sep. 19, 2023**

(54) **SEAL STRUCTURE OF A BODY**

- (71) Applicant: **Transportation IP Holdings, LLC**, Norwalk, CT (US)
- (72) Inventors: **Uday Prakash Karmarkar**, Erie, PA (US); **Dennis Richter**, Lawrence Park, PA (US); **Krishna Kumar Gupta**, Bangalore (IN); **Jaime Jesus Garcia**, Erie, PA (US); **Erik W. Miller**, Erie, PA (US)
- (73) Assignee: **Transportation IP Holdings, LLC**, Norwalk, CT (US)

(**) Term: **15 Years**

(21) Appl. No.: **29/714,322**

(22) Filed: **Nov. 22, 2019**

(51) LOC (14) Cl. **23-01**

(52) U.S. Cl.

USPC **D23/269**

(58) **Field of Classification Search**

USPC D23/259, 262, 269; D13/154

CPC B33Y 80/00

See application file for complete search history.

(57) **CLAIM**

The ornamental design for a seal structure of a body, as shown and described.

DESCRIPTION

FIG. 1 is a perspective view of a seal structure of a body showing our new design;

FIG. 2 is a front side view of the seal structure of a body; FIG. 3 is a rear side view of the seal structure of a body; FIG. 4 is a top plan view of the seal structure of a body; FIG. 5 is a bottom plan view of the seal structure of a body; FIG. 6 is a left side view of the seal structure of a body; FIG. 7 is a right side view of the seal structure of a body; and,

FIG. 8 is a cross-sectional view taken along line 8-8 of FIG. 7.

The broken lines illustrate portions of the body that form no part of the claimed design.

1 Claim, 4 Drawing Sheets
